UNITED STATES PATENT OFFICE.

FRANK L. ROSENTRETER, OF ROCHESTER, NEW YORK, ASSIGNOR TO THE CALDWELL MANUFACTURING COMPANY, OF NEW YORK.

DESIGN FOR A GARMENT-HANGER.

SPECIFICATION forming part of Design No. 32,595, dated April 24, 1900.

Application filed April 17, 1899. Serial No. 713,414. Term of patent 7 years.

To all whom it may concern: .

Beit known that I, FRANK L. ROSENTRETER, a citizen of the United States, and a resident of Rochester, in the county of Monroe and 5 State of New York, have invented and produced a certain new and original Design for a Garment-Hanger, of which the following is a specification.

This design relates to garment-hangers.

10 In the drawing the figure is a perspective view of a garment-hanger, showing my new design.

As shown in the drawing, the leading or 15 material feature of my design consists of the loop - shaped downwardly - curved similar skeleton arms A and the support between said

arms, which latter is depressed beneath the junction a of said arms into the loop B and then extended upward and slightly forward in the portion C until above said point a, and 20 thence backward over the said loop in the convex curve D, as shown in the figure, and finally terminating in the curved hook E set transversely to the plane of the portions B, C, and D. 25

What I claim is—

The design for a garment-hanger, as herein shown and described.

FRANK L. ROSENTRETER.
